CLAIM

The ornamental design for a miter saw, as shown and described.

DESCRIPTION

FIG. 1 is a perspective view of portions of a miter saw according to the invention.

FIG. 2 is a front view of the portions of the miter saw of FIG. 1.

FIG. 3 is a rear view of the portions of the miter saw of FIG. 1.

FIG. 4 is a right side view of the portions of the miter saw of FIG. 1; and,

FIG. 5 is a top plan view of the portions of the miter saw of FIG. 1.

The broken lines in the drawings depict portions of the miter saw which form no part of the claimed design.

1 Claim, 5 Drawing Sheets
